Primary Examiner—Ian Simmons*Assistant Examiner*—Mark A Goodwin(74) *Attorney, Agent, or Firm*—Patterson, Thuente, Skaar & Christensen, PA(57) **CLAIM**

I claim the ornamental design for portable levee system, as shown and described.

DESCRIPTION

FIG. 1 is a side view of a portable levee system in accordance with the present invention.

FIG. 2 is a top view of a portable levee system of the present invention.

FIG. 3 is a rear perspective view of a portable levee system of the present invention; and,

FIG. 4 is a front view of a portable levee system of the present invention.

The portions of the figures shown in broken lines are for illustrative purposes and form no part of the claimed design.
